UNITED STATES PATENT OFFICE.

KATHRYN M. CONNALLY, OF CHICAGO, ILLINOIS.

SAFETY GUARD FOR EARRINGS.

Application filed February 19, 1923. Serial No. 620,044.

To all whom it may concern:

Be it known that I, KATHRYN M. CONNALLY, a citizen of the United States, and a resident of Chicago, in the county of Cook and State of Illinois, have invented a new and useful Improvement in Safety Guards for Earrings, of which the following is a full, clear, and exact description.

My invention relates to improvements in safety guards for ear rings, and it consists in the combinations, constructions, and arrangements herein described and claimed.

An object of my invention is to provide a guard that will serve to prevent the loss of the ear ring through the unintentional loosening or breakage of the fastening means. The ordinary type of ear ring is provided with a screw clamp that is pressed into the lobe of the ear to hold the ear ring in place. It is not an uncommon occurrence for this clamp to become loosened and the ear ring lost without knowledge of the occurrence to the wearer.

A further object of my invention is to provide a safety guard for ear rings which is practically invisible, since the greatest part of the guard is disposed behind the ear.

A further object of my invention is to provide a device of the character described that is simple in construction, durable, and thoroughly practical commercially.

Other objects and advantages will appear in the following specification, and the novel features of the invention will be particularly pointed out in the appended claim.

My invention is illustrated in the accompanying drawings, forming part of this application, in which—

Figure 1 is a perspective view of an embodiment of my invention operatively applied.

In carrying out my invention, I make use of the ordinary type of ear ring 1 having ornaments 2 supported by a stirrup 3. The stirrup 3 is provided with a substantially smooth rounded portion 4 which may be referred to as the pad. A threaded locking bar or screw 5 is carried by the opposite branch of the stirrup and is in alinement with the pad 4. The screw 5 is provided

with a suitable clamping surface 6 and a knurled knob 7 by means of which the screw 5 may be turned.

So far, the structure defined is structure common to the ordinary type of ear ring. 55 My improvement or safety guard, which is attached to the ear ring comprises a chain 8 having a ring 9 at the lower end thereof, which ring is disposed concentric the stirrup 3. This ring 9 is the ordinary spring 60 closed type and may be opened manually by means of the bolt 10 so that it may be removed from the stirrup or replaced at will.

A resilient hook 11 is secured to the opposite end of the chain 8, as shown at 12. This hook 11 is formed so that it will closely grip that portion of the human ear intermediate the head and the shell of the ear.

It will be apparent therefore that the 70 guard is practically concealed by the shell part of the ear and therefore does not present an obtrusive appearance if the person wearing the ear rings chooses to dress the hair above the ears. 75

From the foregoing description of the various parts of the device, the operation thereof may be readily understood. Let us assume that the ear ring shown in Figure 1 is worn upon the ear of a person, and that 80 the screw 5 has gradually become loosened without knowledge to the wearer. When the screw becomes sufficiently loose, the ear ring may drop free of the lobe of the ear. This is not an uncommon occurrence, especially in the case of the ear ring having 85 relatively heavy ornaments which styles decree from time to time.

In the present case, the ear ring will not drop to the floor and become lost, but will 90 drop only as far as the chain 8 permits. The presence of the loosened ear ring will at once become detected, since it will hang loosely adjacent the ear of the wearer and its presence will be at once felt. 95

I claim:

A device of the type described comprising a U-shaped body portion, an ornament carried by one arm of said U-shaped member, a manually-actuated screw carried by 100

2

the other arm, an ear-engaging member disposed at the inner end of said screw, a pendant slidably disposed on said U-shaped arm and carrying an ornament, and means removably and slidably secured to said U-shaped member for connecting the device to the ear, said means comprising a hook-shaped member for removably engaging with the ear, an eyelet clasp removably disposed upon said U-shaped member and being adapted to slide therealong, and a chain connecting said clasp to said hook-shaped member. 10

KATHRYN M. CONNALLY.
